ABSTRACT OF THE DISCLOSURE

A combustion device is mounted in a sealed enclosure for safety. The adjustments of the fuel and air supplied to the device are adjusted with mechanical linkage which is extended from their connection to the burner to a position external of the sealed enclosure.

BACKGROUND OF THE INVENTION

Field of the invention

The present invention relates to the remote control of elements supplied to support a combustion process. More particularly, the invention relates to mechanical linkage which is arranged as means whereby the fuel and air flowing to a burner is regulated through the wall of a sealed housing within which the burner is mounted.

Description of the prior art

Linkage extended through isolating walls has been developed in many forms. A linkage member rotated in a sealing structure mounted in a wall represents one such form.

Burners which have an adjustment for air and a separate adjustment for fuel should have as few sealing structures as possible in the wall of their housing for access to both adjustments. A form of telescoping linkage is a generally desirable concept. This form would facilitate the use of a single sealing structure. A problem descends upon this concept in keeping these adjustments independent of each other in operation while sharing a common sealing structure.

SUMMARY OF THE INVENTION

A principal object of the invention is to make both the fuel and air adjustments of a combustion burner through a common sealing structure in a housing wall for the burner.

Another object is to make the adjustments independent of each other.

The present invention contemplates a mechanical linkage comprised of a first elongated link rotated with threaded engagement through a sealed housing wall and extending from connection with an air flow control structure of a burner to a point external the housing. A second elongated link extends along the central bore of the first link with threaded engagement to connect between a fuel flow control structure of a burner and a point external of the housing. A first nut member is arranged to fix the first link to the housing after adjustment. A second nut member fixes the two links together after adjustment.

Other objects, advantages and features of this invention will become apparent to one skilled in the art upon consideration of the written specification, appended claims, and attached drawing, wherein;

The drawing is a partially sectioned elevation of a portion of a burner and wall of a housing with a linkage embodying the present invention.

2

DESCRIPTION OF THE PREFERRED EMBODIMENT

In the drawings, part of an industrial burner 1 is disclosed as mounted within a housing which isolates the burner from hazardous fluids. The specific duty of the burner 1 is not indicated. It is only necessary to indicate that the burner is within a housing and there descends the problem of adjusting fuel and air supplies to the burner from outside the housing.

The problem further contracts to extending some form of linkage through wall 2 to actuate the regulating mechanisms for fuel and air. Fuel flows into the burner through conduit 3. Air is flowed into the burner between burner end 4 and the end 5 of a yoke member 6 which threads on a central post 7.

A needle valve, not shown, specifically regulates the flow of fuel from conduit 3 into burner 1. Post 8 threads axially inside post 7 and rotation of this post 8 determines the amount of fuel discharged into the burner to propagate combustion.

The air, mixed with the fuel, is specifically regulated by the distance between end 4 and end 5. Air flows through this opening and mixes with the fuel of conduit 3 within burner 1. Rotation of yoke 6 on post 7 determines the size of the opening for this air flow.

The invention includes the linkage from yoke 6 and post 8 by which these members are rotated to establish the desired flow rates for fuel and air into burner 1. A screw 9 extends through wall 2 and connects to post 8 through a bracket 10. Screw 9 telescopes within the axial base of screw 11 which screw also extends through wall 1 for connection with yoke 6. Both screw 9 and screw 11 are accessible for rotation outside of wall 2. Located in this arrangement, they provide a system for adjusting the fuel and air of the burner without opening the housing.

The telescopic arrangement of screws 9 and 11 make it possible to extend the assembly through a single opening in wall 2. Sealing about the single opening is relatively simple. A pad plate 12 of suitable thickness is sealed about an opening 13 in wall. A hole is formed through pad 12 and threaded to accommodate threaded screw 11. The threaded engagement is close enough to form the desired seal. A nut 14 is threaded on the outside of screw 11 and can be brought against the surface of plate 12 to lock screw 11 into position.

Screw 9 rotates within the axial bore of screw 11 to adjust the fuel. Nut 15 is threaded on the outside of this screw, and when brought against the end of screw 11 locks the two screws together.

The operation of the structure should now be obvious. Both nut 14 and nut 15 can be locked off and screws 11 and 9 independently adjusted to establish the desired rate of flow to the burner. When the adjustments are correctly made, the nuts 14 and 15 can lock their screws in position on plate 12. The housing remains sealed throughout the adjustment.

From the foregoing it will be seen that this invention is one well adapted to attain all of the ends and objects hereinabove set forth, together with other advantages which are obvious and which are inherent to the apparatus.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawing is to be interpreted as illustrative and not in a limiting sense.

The invention having been described, what is claimed is:

1. A remote actuation system for an isolated industrial burner, including,
a housing for an industrial burner,
an industrial burner mounted with the housing,
valves on the burner which are mechanically actuated
to regulate the flow of fuel and air into the burner,
screw members of elongated form and telescoped together
and attached to the valves so the valves will
be individually actuated when the screws are rotated,
a single packing for the telescoped screw members
arranged between a wall of the housing and the members,
means for locking the screws in position relative to
the housing.
2. The system of claim 1 including,
a valve for the fuel connected to the screw member
telescoped within the axial base of the other screw
member, and
a yoke member on the outside of fuel valve and con-
nected to the air valve and the other screw member,

5
10
15
20
whereby each valve is individually actuated without interference with one another.

3. The system of claim 1 wherein,
the locking means is a nut threaded to the outside of
each screw member, the nut on the external screw
member brought against the housing wall and the
nut on the internal screw member brought against
the end of the external screw member.
